(57) **CLAIM**

The ornamental design for a watch band, as shown and described.

DESCRIPTION

FIG. 1 is a front perspective view of a watch band, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is a perspective view of the watch band of FIGS. 1-8, shown in a clasped position in an environment of use.

The figures include surface shading and stippling, which represents contour and not surface ornamentation.

The longer broken lines contained within stippled areas of the figures represent stitching and form no part of the claimed design.
